Primary Examiner — Mitchell I. Siegel(74) *Attorney, Agent, or Firm* — Sullivan & Worcester LLP(57) **CLAIM**

I claim the ornamental design for a racket handle, as shown and described.

DESCRIPTION

FIG. 1 is a front perspective view of a racket handle according to one embodiment of my new design.

FIG. 2 is a left side view thereof;

FIG. 3 is a right side view thereof;

FIG. 4 is another side view thereof;

FIG. 5 is another side view thereof; and

FIG. 6 is a top view thereof;

FIG. 7 is a bottom view thereof; and,

FIG. 8 is a reduced perspective view thereof. The unclaimed portions of the racket form no part of the claimed design. The broken lines in the drawings show portions of the racket that form no part of the claimed design.
